UNITED STATES PATENT OFFICE.

ALBERT THODE, OF HAMBURG, GERMANY.

TROLLEY-CATCHER.

SPECIFICATION forming part of Letters Patent No. 716,145, dated December 16, 1902.

Application filed September 25, 1902. Serial No. 124,863. (No model.)

To all whom it may concern:

Be it known that I, ALBERT THODE, a subject of the German Emperor, and a resident of Hamburg, in the German Empire, have invented 5 certain new and useful Improvements in Trolley-Catchers, of which the following is a specification.

This invention has relation to trolley-catchers for overhead electrical-conduit systems, 10 and more particularly refers to improvements in trolley - catch devices for contact - roller or trolley - poles (especially for electrically-driven street-cars) of the class in which when the trolley-holder slips off the current-supplying wire a cord is drawn off a spring-controlled cord pulley or "drum," whereby one or more arresting levers or pawls pivoted to the said drum are caused to swing outward, the ends of such pawls being adapted to engage in a 15 toothed rim wherewith the drum-easing is fitted, and thus prevent any further rotation of the cord-drum, so that the cord maintaining the trolley-pole cannot be further unwound from such drum when in such intercepting 20 devices the tension of the retaining-cord is temporarily relaxed or when by "whipping down" the trolley-pole such tension ceases altogether the arresting-lever pawls are by their 25 springs swung out of engagement with the toothed rim and back to their position of rest. The mutual arresting action between the cord-drum and drum-case in that case is put an 30 end to and does not recommence until after the trolley-pole by springing forward or upward, and thereby drawing off a further length 35 of cord, sets the cord-drum in sufficiently rapid motion. It will therefore be seen that the reliable locking and retaining of the trolley-pole are not effected where such intercepting 40 devices as above described are used.

Now the object of this invention is to obviate this disadvantage, first, by retaining the trolley-pole, if it should slip off the conducting-wire, in a firm and reliable manner, and, 45 further, by preventing under all circumstances any further unwinding of the holding-cord from the cord-drum. The desired object is attained by providing the cord-drum with a special spring-actuated arresting-pawl 50 (or, if preferred, more than one such spring catch or pawl) and utilizing the outward os-

cillation of weighted swing-levers in releasing such special pawl or pawls, which thereupon are each by its spring immediately pressed into engagement with the toothed rim 55 of the drum-case and caused to lock the cord-drum in position irrespective of any swinging or whipping movements of the trolley-pole until the pawl has been released and brought back to its initial position by means of a spe- 60 cial handle.

In order that my invention may be more fully understood, I shall now proceed to describe the same in detail, reference being taken for that purpose to the accompanying 65 sheet of drawings, wherein—

Figure 1 is a vertical section on the line A B, Fig. 2, and Fig. 2 a horizontal section on the line C D, Fig. 1, of my improved catch device for trolley-holders.

Similar letters of reference refer to similar parts throughout the several figures.

According to this invention the case *a*, which by means of an extension or projection *a'* is secured or suspended at a convenient 75 point in any suitable manner, is fitted with an inner rim with ratchet-teeth *b* and with a central-pivot or spindle *c*, upon which latter is mounted the cord-drum *d*, whereon the cord *e*, which holds the trolley-holder, (not shown,) 80 is wound.

A spiral spring *f*, housed in the interior of the cord-drum, one end of which is secured to the drum *d* and the other end to the afore-said central spindle or pivot *c*, tends so to 85 turn the drum as to cause any slack of the holding-cord *e* to be always wound onto such drum—in other words, so that the movement of unwinding or drawing off the said cord is at all times resisted by spring tension. 90

Onto the inward end surface of the drum *d* there are revolvably secured at *h* and *h'* appropriate swing-levers *g* and *g'*, constructed in the form of centrifugal weights and connected with each other by a rod or link *i*, so 95 as to insure uniformity in their respective movements. To one of the swing-levers, in the present case to the lever *g*, is further attached a flat spring *k*, which with its free-end rests upon a pin *l* and tends to maintain said 100 swing-levers in the position shown and also after the completion of their outward swing-

ing movement to restore them to that position. The amplitude of the swing-levers may be controlled, if desired, by a stop-pin g^2 . On the same end surface of the cord-drum 5 there is further arranged an arresting-pawl m , the pivot n of which is extended through the drum to the opposite side of it and is at the other end provided with a handle o . A flat spring p , secured to the arresting-pawl m , the 10 free end of which rests upon a pin q , tends to swing said arresting-pawl into the arresting position, (shown by dotted lines in Fig. 1,) in which position the point of the pawl acts against the teeth b of the aforesaid toothed 15 rim, so that the cord-drum is secured against rotary motion.

To the swing-lever g is attached an arresting-hook r , which passes over and engages with a pin s on the aforesaid arresting-pawl m 20 the moment the said pawl is by means of the handle o swung inward in opposition to the pressure of its spring. It follows that the hook r maintains the pawl m in a state of tension. This cocked position of the arresting- 25 pawl m is shown in Figs. 1 and 2.

The operation of the improved catch device is as follows: Should the trolley slip off the conducting-wire, it immediately jumps upward and draws the cord e off the drum d , 30 whereby such drum is set in rotary motion. As the drum rotates, the weighted swing-levers g g' oscillate and the hook r releases the arresting-pawl m , which thereupon is instantly by its spring swung outward into 35 engagement with the toothed rim, thereby locking the drum in position within the drum-case a . The arresting-pawl m , which produces the locking effect described independently of the weighted swing-levers, will retain the cord-drum in the locked position, 40 even if the weighted swing-levers, in the event of the pull upon the cord being relaxed or discontinued altogether, happen to be allowed to swing back to their position of rest. The 45 intermittent or step-by-step release of the arrested cord-drum, to which reference has been made in the introduction or preamble and which is effected by the whipping or swinging movements of the trolley-pole when it 50 happens to have left the conducting-wire, is here entirely avoided by the independent locking action of the arresting-pawl m . If after the trolley-pole has been replaced in contact with the conducting-wire and properly 55 adjusted it be desired to release the arresting-pawl and to move it back to its previous cocked position, it is swung inward by means of the handle o until its pin s engages with the hook r , or until this hook snaps or 60 springs over the said pin. The catch device is then ready for use once more, so that if the trolley-holder should again slip or jump off the conducting-wire it will immediately secure the cord-drum in place as before.

65 Having fully described my invention, what

I claim, and desire to secure by Letters Patent, is—

1. A trolley-catcher, comprising a trolley-operating rope-winding mechanism, locking mechanism connected thereto, a support 70 adapted to be engaged by the locking mechanism, means constantly tending to move said locking mechanism into engagement with the support, and restraining mechanism restraining said movement of the locking mechanism, said restraining mechanism influenced by centrifugal action to release the locking mechanism; in combination with means for disengaging the locking mechanism from the support and moving it into engagement with the restraining mechanism, for the purpose set forth.

2. A trolley-catcher, comprising a trolley-operating rope-winding mechanism, locking mechanism connected thereto, a support 85 adapted to be engaged by the locking mechanism, means constantly tending to move said locking mechanism into engagement with the support, and restraining mechanism restraining said movement of the locking mechanism, 90 said restraining mechanism influenced by centrifugal action to release the locking mechanism; in combination with means to be operated by hand to disengage the locking mechanism from the support and move it into engagement with the restraining mechanism, for the purpose set forth.

3. A trolley-catcher comprising a trolley-rope-winding drum, locking mechanism connected thereto, a support adapted to be engaged by the locking mechanism and organized to lock the drum against rotation in one direction only, means constantly tending to move the locking mechanism into engagement with said support, and a restraining mechanism restraining said movement of the locking mechanism, said restraining mechanism influenced by centrifugal action to release said locking mechanism; in combination with means to be operated by hand, for disengaging the locking mechanism from the support and moving it into engagement with the restraining mechanism, for the purpose set forth.

4. A trolley-catcher, comprising an internally-toothed casing, a trolley-operating rope-winding drum, a locking-pawl pivoted thereto and adapted to engage the teeth on the casing, a spring acting on the pawl to move the same into engagement with said teeth, and weighted levers linked together for mutual 105 operation, one of said levers provided with a catch adapted to engage the pawl; in combination with hand-operated means for disengaging the pawl from the teeth of the drum and moving it into engagement with the afore- 110 said catch, for the purpose set forth.

ALBERT THODE.
